UNITED STATES PATENT OFFICE.

CHARLES LANGTON CLARKE, OF TORONTO, ONTARIO, CANADA, ASSIGNOR
OF ONE-FIFTH TO CHARLES JAMES CROWLEY, OF SAME PLACE.

TOBACCO-PIPE.

SPECIFICATION forming part of Letters Patent No. 390,453, dated October 2, 1888.

Application filed October 20, 1887. Serial No. 253,918. (No model.) Patented in England September 13, 1887, No. 12,411.

To all whom it may concern:

Be it known that I, CHARLES LANGTON CLARKE, of the city of Toronto, in the county of York, in the Province of Ontario, Canada, have invented a certain new and useful Improvement in Tobacco-Pipes, (for which I have obtained Letters Patent in Great Britain September 13, 1887, No. 12,411,) of which the following is a specification.

10 The object of the invention is to provide a tobacco-pipe of ordinary length and capable of being carried in a pocket-case, wherein all the advantages of a pipe with a lengthened stem in the way of cooling the tobacco-smoke are attained, the smoke being caused to pass through channels which traverse the stem longitudinally three times before being drawn into the mouth of the smoker through the mouth-piece, as hereinafter more particularly 15 explained.

20 The novelty resides in the peculiarities of construction, substantially as hereinafter more fully described and claimed.

Figure 1 is an enlarged perspective view of 25 my improved pipe, the upper half of mouth-piece, stem, neck of bowl, and bowl having been cut away so as to exhibit my device. Fig. 2 is an enlarged sectional detail. Fig. 3 is a perspective detail.

30 A is the bowl of the pipe, partly broken away so as to show the orifice at a in the bottom of the bowl, through which the smoke is drawn into the stem.

B is the neck of the bowl, the end of which 35 at b butts up against the end of the stem D. This joint at b is covered, and the parts B and D are held together by the ferrule C, which is attached to the stem D. Instead of the stem being fastened to the neck of the bowl by a 40 ferrule, it may be screwed on the neck in the usual manner.

E is a tube, preferably of metal, closed at the end nearest to the bowl and rigidly attached to the neck B of the bowl in a recess formed 45 therein, the end which projects beyond the neck of the bowl being fitted into a recess or enlargement at e of the smoke-passage 3, and is cut out at the end of the stem.

f is a small tube open at both ends, which 50 fits tightly into an enlargement of the smoke-passage 1 at the end of the neck of the bowl,

the end which projects slightly beyond the end of the neck of the bowl being adapted to fit into an enlargement of the smoke-passage 1. This small tube f is here placed to prevent any 55 leakage of smoke-passage 1 at the joint covered by the ferrule C.

F is a mouth-piece, preferably of amber, with screw g fastened thereto in the usual manner and adapted to screw into the screw-recess h, 60 formed at the mouth-piece end of the stem D. The inner portion of the stem surrounding this screw g is cut away, so as to form a circular passage-way or channel, k, for the smoke from smoke-passage 1 to smoke-passage 2 at the 65 opposite side of the pipe-stem, the end of the mouth-piece F, when screwed down on the stem, forming a covering for this circular smoke-passage. The stem and neck of the bowl are preferably elliptical in shape, as indicated, so as to afford room for the three smoke-passages 1, 2, and 3. The end of smoke-passage 2 near the joint which is covered by the ferrule is slotted or open, so as to afford a smoke passage or channel leading into 70 smoke-passage 3 through a hole, m, formed in the side of the tube E.

When the smoker uses my improved tobacco-pipe, the smoke is drawn from the bowl along smoke-passage 1 in the direction of 80 the arrow-head, thence across to smoke-passage 2 by the circular passage or channel k, thence along smoke-passage 2 in the direction of the arrow-head through the hole m into smoke-passage 3, and through smoke-passage 3 in the direction of the arrow-head through the mouth-piece F into the 85 smoker's mouth. By the time the tobacco-smoke has reached the smoker's mouth it has traversed the length of the stem three times 90 and is quite cooled down, so as to afford all the advantages of a pipe with a long stem with none of the disadvantages, as my improved pipe can be handily carried in a coat-pocket with or without a case, the stem not being at 95 all in the way or clumsy to carry. My improved pipe can also be readily cleaned by taking it apart and cleaning the stem with the three smoke-passages, the mouth-piece, and bowl in the usual manner. The inside of the 100 ferrule is also readily accessible for cleaning. The recess p in the tube E forms a reservoir

for the saliva, so that the saliva from the mouth cannot wet the tobacco in the bowl of the pipe.

I am aware that pipes have been provided with a stem having a plurality of smoke-passages, whereby the smoke is compelled to traverse the stem several times before reaching the mouth of the smoker, and do not seek to cover such construction, broadly, but restrict myself to my peculiar construction and arrangement of parts.

What I claim as my invention is—

1. The combination, with the bowl having neck B and orifice *a*, of the stem D, having smoke-passages 1, 2, and 3, the ferrule C, covering the joint between the stem and bowl, the tube secured in a recess in the neck of the bowl and closed at the bowl end, with its other end fitted in a recess in the smoke-passage 3, the tube *f*, fitted into a recess in the end of the

bowl and in the passage 1, and a mouth-piece 20 having a passage communicating with the passage 3, substantially as described.

2. In an improved tobacco-pipe, the combination, with the stem D, pierced with longitudinal smoke-passages 1, 2, and 3 and smoke-passage *k*, of the mouth-piece F, the tube E, having smoke-passage *m*, communicating with the passages 2 and 3, pipe *f*, fitted into an enlargement of the passage 1, saliva-reservoir *p*, in the bowl end of the tube E, the ferrule C, 25 and the pipe-bowl A, having a neck, B, pierced with smoke-tube, substantially as described and specified.

Toronto, July 13, 1887.

C. LANGTON CLARKE.

In presence of—

JOHN G. RIDOUT,
CHARLES C. BALDWIN.
